UNITED STATES PATENT OFFICE.

SIGMUND L. LEDERER, OF NEW YORK, N. Y.

DESIGN FOR AN ORNAMENTAL CHAIN-LINK.

SPECIFICATION forming part of Design No. 13,718, dated March 13, 1883.

Application filed January 2, 1883. Term of patent 14 years.

To all whom it may concern:

Be it known that I, SIGMUND L. LEDERER, a citizen of the United States, residing at New York, in the county and State of New York, have invented and produced a new and original Design for Ornamental Chain-Links, of which the following is a full, clear, and exact description, reference being had to the accompanying drawings, forming part of this specification.

Figure 1 is a view of one form of my newly-designed chain-link. Fig. 2 is a modification of the same. Fig. 3 is another modification of the same, and Fig. 4 is still another modification of the same. Fig. 5 is an end view of my newly-designed chain-link. Fig. 6 is a view of a chain made up of my newly-designed ornamental links.

Heretofore ornamental chain-links have been made of flat stock, so as to produce four wings or flat sides radiating from the center, forming, in section, the shape of a cross.

The leading feature of my design consists in surrounding such chain-links with one or more circular rings, and thereby produce a new and original design.

In the drawings, *aa* are the four wings forming the chain-link. These wings are flat pieces of metal, radiating from the center outward. They are usually made in section of the form of a cross; but three wings may be used instead of four. They may be of any desired form or outline, such as are shown in the different figures of the drawings, or any other desired form.

bb are rings surrounding the chain-link proper and inclosing the wings. These rings *bb* may be made of round or flat stock. They may be narrow or wide to suit the taste, and they may be partially or wholly embedded in notches cut into the wings *aa* or set on the edge. These rings may be of the same color as the wings, or of different color, so as to produce a contrast.

My newly-designed ornamental chain-links are usually made of bright gold, silver, or gilded metal. The effect produced by the combination with the radiating flat surfaces of the wings of the rings is agreeable, and gives a marked, readily-distinguishable appearance to the chain-links and to ornamental chains made up of such links.

Having thus described my invention, I claim as new and desire to secure by Letters Patent—

1. The design for ornamental chain-links herein shown and described, the same consisting of a link formed of the flat wings *aa*, surrounded by the ring *bb*, as described.

2. The design for ornamental chain-links herein shown and described, the same consisting of a link formed of the flat wings *aa*, radiating from the center of the link, surrounded by one or more rings, *bb*, as described.

3. An ornamental chain, consisting of links having radiating flat sides *aa*, surrounded by one or more rings, as described.

SIGMUND L. LEDERER.
